2/26/31

UNITED STATES PATENT OFFICE

JOHANN EINFALT, OF NUEREMBERG, GERMANY

SHEET METAL TOY SHIP HULL

Application filed February 26, 1931, Serial No. 518,467, and in Germany July 25, 1930.

It is already known to watertightly connect the seams of two hull halves by folding or soldering. It is also known, to make the hull of a toy ship from one piece of sheet metal. Neither of these methods of producing hulls however enables a sharp pointed stem to be produced.

This invention relates to a method of producing a sheet metal ship's hull, bent from one piece of sheet metal, in which the stem tapers to a point and is bent watertightly together.

The accompanying drawings illustrate the method of producing a ship's hull.

15 Fig. 1 is a top plan view of a sheet metal blank.

Fig. 2 is a top plan view of a blank, in which the stem is partly folded in.

20 Fig. 3 is a front elevation of Fig. 2.

Fig. 4 shows in top plan view the hull completely drawn.

Fig. 5 is a side elevation of Fig. 4.

The blank composed of the bottom *a* and of the side walls *b* of the hull is cut as shown 25 in Fig. 1, the stem portion *c* being preferably in the form of a quadrangle with unequal sides.

In the second operation, Figs 2 and 3, the quadrangle *c* is bent upwards by a die *d*. 30 The die *d* is also of quadrangular shape; so that at the middle at *f* a fold is formed. The side walls *b* are also bent upwards at the front end at this operation.

35 In the third operation the hull is placed in a matrix and drawn to any desired shape by means of a matrix. During this operation the bent up quadrangle is completely drawn in so that the shape shown in Figs 4 and 5 is produced.

40 The hull drawn according to this operation has a pointed shape at the stem and is watertightly joined.

45 The deck is then put on in a fourth operation and holds the folded portion tightly together.

As shown in Fig. 5 the quadrangle is bent upwards so that water cannot penetrate into the hull.

50 If desired a metal strip may be used for

better holding together the two hull parts.

I claim:—

A method of producing a sheet metal toy ship's hull, consisting in stamping a sheet metal blank comprising a bottom, side parts 55 and an extension of quadrangular shape at the front end, in bending up this extension by means of a quadrangular die so that a fold is formed in the bent up extension, in drawing the hull so that this bent up extension is 60 inside the hull and a pointed stem is obtained, and in watertightly connecting both side parts of the hull.

In testimony whereof I affix my signature.
